US0D1045806S

(12) **United States Design Patent** (10) **Patent No.:** **US D1,045,806 S**
(45) **Date of Patent:** **** Oct. 8, 2024**

(54) **STARLINK CABLE**

(71) Applicant: **Shenzhen Starlink Origin Network Technology Co., Ltd.**, Shenzhen (CN)

(72) Inventor: **Yong Xu**, Chongqing (CN)

(73) Assignee: **Shenzhen Starlink Origin Network Technology Co., Ltd.**, Shenzhen (CN)

(**) Term: **15 Years**

(21) Appl. No.: **29/922,152**

(22) Filed: **Dec. 20, 2023**

(51) LOC (14) Cl. **13-03**

(52) U.S. Cl.

USPC **D13/153**

(58) **Field of Classification Search**

USPC D13/153, 110, 199; D14/205

CPC F16G 3/04; H04M 1/725

See application file for complete search history.

(57) **CLAIM**

The ornamental design for a starlink cable, as shown and described.

DESCRIPTION

FIG. 1 is a front perspective view of a starlink cable, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The broken lines in the drawings illustrate portions of the starlink cable, which form no part of the claimed design.
